Primary Examiner — Wendy L Arminio*Assistant Examiner* — Maheen Khurshid(74) *Attorney, Agent, or Firm* — Georgi Korobanov(57) **CLAIM**

The ornamental design for an electric breast pump, as shown and described.

DESCRIPTION

FIG. 1 is a front, top left side perspective view of an electric breast pump, showing my new design;
FIG. 2 is a rear, bottom right side perspective view thereof;
FIG. 3 is a front, top left side exploded view thereof;
FIG. 4 is a front view thereof;
FIG. 5 is a rear view thereof;
FIG. 6 is a left side view thereof;
FIG. 7 is a right side view thereof;
FIG. 8 is a top plan view thereof; and,
FIG. 9 is a bottom plan view thereof.

(Continued)

The broken lines shown in the drawings illustrate portions of the electric breast pump that form no part of the claimed design.
